CLAIM

The ornamental design for a browband, as shown and described.

DESCRIPTION

FIG. 1 is a top perspective view of a browband in accordance with the present teachings.

FIG. 2 is a front view of the browband of FIG. 1.

FIG. 3 is a top view of the browband of FIG. 1.

FIG. 4 is a bottom view of the browband of FIG. 1.

FIG. 5 is a rear view of the browband of FIG. 1.

FIG. 6 is a right side view of the browband of FIG. 1.

FIG. 7 is a left side view of the browband of FIG. 1.

FIG. 8 is a bottom perspective view of the browband of FIG. 1.

FIG. 9 is an enlarged view of the browband of FIG. 2.

FIG. 10 is an enlarged view of the browband of FIG. 2.

FIG. 11 is an enlarged cross-sectional view of the browband of FIG. 2; and,

FIG. 12 is an enlarged cross-sectional view of the browband of FIG. 2.

The broken lines in the figures are for the purpose of depicting portions of a browband and form no part of the claim.
